FIG. 1 is a front perspective view of one embodiment of a picture frame or similar article showing my new design wherein the upper surface thereof is canted;

FIG. 2 is a front elevational view thereof;

FIG. 3 is a rear elevational view;

FIG. 4 is a side elevational view; and

FIG. 5 is a side elevational view of another embodiment of the picture frame or similar article shown in FIG. 1 wherein the upper surface thereof is horizontal.

The undisclosed opposite sides of FIGS. 4 and 5 present a mirror image of each of the respective sides disclosed.

The dominant features of the design reside in the portions shown in solid lines; a conventional picture being shown in broken lines in FIGS. 1 and 2.

I claim:

The ornamental design for a picture frame or similar article, as shown and described.
